(57) CLAIM

The ornamental design for a display screen with icon group and display screen with icon set, as shown and described.

DESCRIPTION

FIG. 1 is a front view of a display screen with icon group showing our new design;

FIG. 2 is an enlarged view of the claimed portion as shown in FIG. 1 shown as an icon group with environment removed for clarity purposes; and,

FIG. 3 is a view of the claimed portion as shown in FIG. 2 shown as an icon set.

The uneven-length broken line defines the bounds of the claimed design and forms no part thereof. The even-length broken line showing of the text, the circular-shaped regions, and the remainder of the display screen forms no part of the claimed design.
